DESIGN FOR A POCKET FLASHLIGHT

Isaac L. Ferris, Bridgeport, Conn., assignor to The Bridgeport Metal Goods Manufacturing Company, Bridgeport, Conn., a corporation of Connecticut

Application October 17, 1938, Serial No. 80,496

Term of patent 7 years

To all whom it may concern:

Be it known that I, Isaac L. Ferris, a citizen of the United States, residing at Bridgeport, county of Fairfield, State of Connecticut, have invented a new, original, and ornamental Design for a Pocket Flashlight, of which the following is a specification, reference being had to the accompanying drawing, forming part thereof.

Fig. 1 is a plan view of a pocket flashlight showing my new design;

Fig. 2 is an edge view thereof; and

Fig. 3 is an end view looking toward the top of Figs. 1 and 2.

The side opposite to Fig. 1 is substantially the same in appearance except that the switch is omitted.

I claim:

The ornamental design for a pocket flashlight, substantially as shown and described.

ISAAC L. FERRIS.
